ABSTRACT OF THE DISCLOSURE

An antiredposition agent having special utility in the washing of synthetic fabrics, synthetic-cotton blends, cotton fabrics, and mixtures thereof, which consist essentially of (a) from about 40% to about 95% alkali metal carboxymethylcellulose having a DS within the range of from about 0.4 to about 1.5 and a DP within the range of from about 200 to about 4000; and (b) from about 5% to about 60% hydroxypropylcellulose having an MS within the range of from about 2 to about 5 and a DP within the range of from about 100 to about 1200.

This invention relates to a novel antiredposition agent for use in built detergent compositions. More specifically, the invention involves an antiredposition agent which exhibits about the same level of efficacy as the best currently known antiredposition agents in regard to conventional cotton fabrics and exhibits a high level of efficacy in regard to modern synthetic fabrics. In essence, the novel antiredposition agent of this invention consists of a certain combination of a specific alkali metal carboxymethylcellulose and a specific hydroxypropylcellulose. Hereinafter, alkali metal carboxymethylcellulose and hydroxypropylcellulose are referred when appropriate as CMC and HPC, respectively.

Combinations comprising CMC and a hydroxyalkylcellulose, e.g., HPC, have been disclosed as antiredposition agents in U.S. Pat. 2,886,533, granted May 12, 1959 to L. R. Bacon et al. A primary characterizing feature of the present invention resides in the use of a highly specific HPC in the CMC-HPC combination.

Conventional built detergent compositions perform well their function of removing soil and other unwanted matter from fabrics. However, during the washing cycle, some of the removed soil tends to redeposit on the fabric. Thus, it is common to incorporate an antiredposition agent in built detergent compositions. An antiredposition agent retards the removed soil from redepositing on the washed fabric.

CMC is currently the most popular and widely used antiredposition agent. A large number of commercially available built detergent compositions, either for household or industrial use, contain CMC, and the antiredposition efficacy of CMC is well known. However, it is also well known to those skilled in the art that such efficacy is achieved only with cotton fabrics and that CMC has essentially no antiredposition effect when the material to be washed is a synthetic fabric or a synthetic-cotton blend.

It is highly desirable to discover an antiredposition agent which is effective with synthetic fabrics or synthetic-cotton blends, e.g., polyamides such as nylon; polyesters such as Dacron® and Kodel®; polyvinyl derivatives such as Orlon®, Creslan® or Dynel®; and cellulose ester fibers such as Arnel®, because of the current widespread use of such materials. The problem is not a simple one, however, because of the fact that antiredposition agents which

have efficacy with synthetic fabrics or synthetic-cotton blends have, in general, an adverse antiredposition effect on cotton. Moreover, as a practical matter, the ordinary load of clothes to be washed consists of a mixture of cotton fabrics, synthetic fabrics and synthetic-cotton blends. Therefore, an antiredposition agent effective with both cotton and synthetic fabrics is in great need but is difficult to achieve.

Accordingly, it is an object of this invention to provide a novel antiredposition agent for use in built detergent compositions.

It is a further object of this invention to provide a novel antiredposition agent for use in built detergent compositions, said agent being effective with synthetic fabrics, synthetic-cotton blends and cotton fabrics.

It is a more specific object of this invention to provide built detergent compositions which contain a novel antiredposition agent and which have special utility in the washing of synthetic fabrics, synthetic-cotton blends, cotton fabrics and mixtures thereof.

The above and other objects can be achieved by a novel antiredposition agent, which consists essentially of:

(a) From about 40% to about 95% alkali metal carboxymethylcellulose having a DS within the range of from about 0.4 to about 1.5 and a DP within the range of from about 200 to about 4000; and

(b) From about 5% to about 60% hydroxypropylcellulose having an MS within the range of from about 2 to about 5 and a DP within the range of from about 100 to about 1200. (DS, DP and MS are defined more fully hereinafter.)

Alkali metal in the above expression is selected from the group consisting of sodium, potassium, lithium and ammonium, of this group, sodium (Na) is highly preferred.

A preferred antiredposition agent of this invention consists essentially of:

(a) From about 65% to about 80% sodium carboxymethylcellulose having a DS within the range of from about 0.4 to about 0.9 and a DP within the range of from about 500 to about 2000; and

(b) From about 20% to about 35% hydroxypropylcellulose having an MS within the range of from about 2 to about 3.5 and a DP within the range of from about 600 to about 1100.

A specific highly preferred antiredposition agent of this invention consists essentially of:

(a) About 71% sodium carboxymethylcellulose having a DS of about 0.7 and a DP of about 1500; and

(b) About 29% hydroxypropylcellulose having an MS of about 2.8 and a DP of about 900.

Another specific highly preferred antiredposition agent of this invention consists essentially of:

(a) About 71% carboxymethylcellulose having a DS of about 0.7 and a DP of about 1500; and

(b) About 29% hydroxypropylcellulose having an MS of about 2.4 and a DP of about 1050.

The above percentages and all others specified herein are by weight. FIGS. I and II are plots illustrating the antiredposition effect of CMC and HPC used individually. FIG. III illustrates the antiredposition effect of a preferred CMC-HPC combination of the invention used at a varying total concentration. FIG. IV illustrates the relationship between antiredposition effect and the ratio of HPC to CMC. FIG. V shows the relationship between antiredposition effect and the MS and DP of the HPC. The DP of the HPC is one of the most critical elements of the present invention. These figures are discussed in detail hereinafter.

The meaning of the terms "degree of substitution" (DS), "MS" and "degree of polymerization" (DP) is given in the following discussion: There are three hy-

droxyl groups in each anhydroglucose unit in the cellulose molecule. DS is the average number of hydroxyl groups substituted in the cellulose per anhydroglucose unit. MS is the average number of moles of reactant combined with the cellulose per mole of anhydroglucose unit. For CMC (or other carboxyalkyl, alkyl or acyl derivatives of cellulose) the DS and MS are the same. For the hydroxyalkyl derivatives of cellulose, e.g., HPC, degree of substitution is generally expressed in terms of MS rather than DS. The reason for this is that each time a hydroxyalkyl group is introduced into the cellulose molecule one hydroxyl group disappears and a new one is formed which itself is capable of hydroxyalkylation. As a result of this, side chains of considerable length may form on the cellulose molecule. Thus, from the foregoing it will be seen that the DS of a cellulose derivative can be no higher than three, whereas the MS may be considerably higher than three depending on the extent to which said chains are formed.

DS values, as expressed herein, are based on calculations according to the Wilson method as disclosed in Svensk Papperstidning 59, 218 (1956). MS values, as expressed herein, are based on calculations according to the Ziesel-Morgan HI ether-cleavage method as disclosed in Industrial Engineering Chemistry 18, 500 (1946).

A second important physical property of cellulose or a cellulose derivative is molecular weight, which is more commonly expressed in terms of degree of polymerization (DP). This in turn is often stated as the degree of polymerization of the cellulose pulp from which the derivative in question is prepared. Therefore, as used herein, DP refers to the viscosity average degree of polymerization of cellulose pulp as determined from the viscosity (V) of 0.5% solutions of cellulose in cupriethylenediamine (1.0 molar in copper, 2.0 molar in ethylenediamine) according to Method T 230 sm-50 of the Technical Association of the Pulp and Paper Industry. The DP is calculated from the formula:

$$DP = 1,439 \log (V) - 387^1$$

The CMC useful in the novel antiredeposition agent of this invention can be prepared by any of the methods known in the art so long as the specified limitations on DS and DP are observed. For example, the CMC can be prepared by the methods disclosed in the copending U.S. patent application of Russell Nelson, Ser. No. 387,378, filed Aug. 4, 1964, and now U.S. Pat. 3,347,855, and in U.S. Pat. 2,553,725.

The hydroxypropylcellulose can also be prepared by methods known in the cellulose art so long as the proper requirements for MS and DP are observed. For example, the HPC can be prepared according to the disclosure in Belgium Pats. 643,558 and 643,559.

It is to be noted that commercially available CMC or HPC often does not comprise 100% of the subject cellulose derivative. For example, a common commercial grade of CMC contains about 61% CMC, the balance being comprised of inert materials consisting essentially of sodium chloride. However, use of this type of material is satisfactory herein so long as the actual amount of CMC or HPC is within the specified range. That is, reference herein to amounts of CMC or HPC is on an active basis.

One of the advantageous features of this invention is the fact that the novel antiredeposition agent is highly effective when used at very low levels in built detergent compositions. More specifically, the built detergent compositions of this invention contain the novel antiredeposition agent in an amount of from about 0.1 to about 1.2%, preferably from about 0.3% to about 0.6%, based on the weight of built detergent composition. The lower limit

¹ DP determined in the way described above is equivalent to DP determined by Method T-238 su-63 of the Technical Association of the Pulp and Paper Industry. According to this method, the DP is calculated from the intrinsic viscosity $[\eta]$ of cellulose nitrate in ethyl acetate by the formula: $DP = 75 [\eta]$.

(0.1%) is the minimum amount of agent required to render clear and desirable antiredeposition results. Significant additional antiredeposition results are not achieved with amounts of agent in excess of the upper limit (1.2%). It is significant and advantageous that this upper limit can be so relatively low because the use of high levels of cellulose materials in detergent compositions, e.g., greater than about 5%, tends to impart undesirable starch-type (stiffening) effects to the fabrics being washed.

As stated above, the built detergent compositions of this invention contain from about 0.1 to about 1.2% of the novel antiredeposition agent. The other essential components are a detergent and a builder salt. These compositions can be prepared in solid or liquid form. The solid, e.g., granular or flake, compositions generally contain from about 5% to about 50% of a detergent component and from about 95% to about 50% of a builder component selected from water-soluble inorganic alkaline builder salts, organic sequestrant builder salts, or mixtures thereof. The liquid compositions generally contain from about 5% to about 40% detergent and from about 95% to about 60% of a water-soluble inorganic alkaline builder salt or organic sequestrant builder salt or mixtures thereof, in a suitable liquid vehicle, e.g., water, alcohol or mixtures thereof. The liquid compositions preferably have a pH ranging from about 9 to about 12, as do the solid compositions when dissolved in aqueous media.

Preferably, the detergent is selected from the group consisting of anionic, nonionic, amphotolytic, zwitterionic detergents and mixtures thereof.

A preferred built detergent composition contains from about 5% to about 25% detergent selected from the group consisting of anionic, nonionic, amphotolytic, zwitterionic detergents and mixtures thereof, and from about 50% to about 70% of builder component selected from the group consisting of water-soluble inorganic alkaline builder salts and organic sequestrant builder salts and mixtures thereof, and from about 0.1% to about 1.2% of an antiredeposition agent as described herein.

The following are specific examples of detergents that can be used in the compositions of the present invention:

(A) ANIONIC SOAP AND NON-SOAP SYNTHETIC DETERGENTS

This class of detergents includes ordinary alkali metal soaps such as the sodium, potassium, ammonium and alkylolammonium salts of higher fatty acids containing from about 8 to about 24 carbon atoms and preferably from about 10 to about 20 carbon atoms. Suitable fatty acids can be obtained from natural sources such as, for instance, from plant or animal esters (e.g., palm oil, coconut oil, babassu oil, soybean oil, castor oil, tallow, whale and fish oils, grease, lard and mixtures thereof). The fatty acids also can be synthetically prepared (e.g., by the oxidation of petroleum, or by hydrogenation of carbon monoxide by the Fischer-Tropsch process). Resin acids are suitable such as rosin and those resin acids in tall oil. Naphthenic acids are also suitable. Sodium and potassium soaps can be made by direct saponification of the fats and oils or by the neutralization of the free fatty acids which are prepared in a separate manufacturing process. Particularly useful are the sodium and potassium salts of the mixtures of fatty acids derived from coconut oil and tallow, i.e., sodium or potassium tallow and coconut soap.

This class of detergents also includes water-soluble salts, particularly the alkali metal salts of organic sulfuric reaction products having in their molecular structure an alkyl radical containing from about 8 to about 22 carbon atoms and a sulfonic acid or sulfuric acid ester radical. (Included in the term alkyl is the alkyl portion of higher acyl radicals.) Examples of this group of synthetic detergents which form a part of the preferred built detergent compositions of the present invention are the sodium or potassium alkyl sulfates, especially those obtained by

sulfating the higher alcohols (C_8 - C_{18} carbon atoms) produced by reducing the glycerides of tallow or coconut oil; sodium or potassium alkyl benzene sulfonates, in which the alkyl group contains from about 9 to about 15 carbon atoms, in straight chain or branched chain configuration, especially those of the type described in United States Letters Pats. Nos. 2,220,099 and 2,477,383; sodium alkyl glyceryl ether sulfonates, especially those ethers of higher alcohols derived from tallow and coconut oil; sodium coconut oil fatty acid monoglyceride sulfonates and sulfates; sodium or potassium salts of sulfuric acid esters of the reaction product of one mole of a higher fatty alcohol (e.g., tallow or coconut oil alcohols) and about 1 to 6 moles of ethylene oxide; sodium or potassium salts of alkyl phenol ethylene oxide ether sulfate with about 1 to about 10 units of ethylene oxide per molecule and in which the alkyl radicals contain about 8 to about 12 carbon atoms.

Additional examples of anionic non-soap synthetic detergents which come within the terms of the present invention are the reaction product of fatty acids esterified with isethionic acid and neutralized with sodium hydroxide where, for example, the fatty acids are derived from coconut oil; sodium or potassium salts of fatty acid amide of methyl tauride in which the fatty acids, for example, are derived from coconut oil. Other anionic synthetic detergents of this variety are set forth in United States Letters Pats. 2,486,921; 2,486,922; and 2,396,278.

Still other anionic synthetic detergents include the class designated as succinamates. This class includes such surface active agents as disodium N-octadecylsulfo succinamate; tetrasodium N-(1,2-dicarboxyethyl)-N-octadecyl-sulfo-succinamate; diamyl ester of sodium sulfosuccinic acid; dihexyl ester of sodium sulfosuccinic acid; dioctyl ester of sodium sulfosuccinic acid.

Anionic phosphate detergents are also useful in the present invention. These are surface active materials having substantial detergent capability in which the anionic solubilizing group connecting hydrophobic moieties is an oxy acid of phosphorous. The more common solubilizing groups, of course, are $-\text{SO}_4\text{H}$, $-\text{SO}_3\text{H}$ and $-\text{CO}_2\text{H}$. Alkyl phosphate esters such as $(\text{R}-\text{O})_2\text{PO}_2\text{H}$ and ROPO_3H_2 in which R represents an alkyl chain containing from about 8 to about 20 carbon atoms are useful.

These esters can be modified by including in the molecule from one to about 40 alkylene oxide units, e.g., ethylene oxide units. Formulae for these modified phosphate anionic detergents are

in which R represents an alkyl group containing from about 8 to 20 carbon atoms, or an alkylphenyl group in which the alkyl group contains from about 8 to 20 carbon atoms, and M represents a soluble cation such as hydrogen, sodium, potassium, ammonium or substituted ammonium; and in which n is an integer from 1 to about 40.

A specific anionic detergent which can be used in the present invention is described more fully in the U.S. patent application of Phillip F. Pflaumer and Adriaan Kessler, Ser. No. 561,397 filed June 29, 1966 and now U.S. Pat. 3,332,880. This detergent comprises by weight from about 30% to about 70% of Component A, from about 20% to about 70% of Component B, and from about 2% to about 15% of Component C, wherein:

(a) Said Component A is a mixture of double-bond positional isomers of water soluble salts of alkene-1-sulfonic acids containing from about 10 to about 24 carbon atoms, said mixture of positional isomers includ-

ing by weight about 10% to about 25% of an alpha-beta unsaturated isomer, about 30% to about 70% of a beta-gamma unsaturated isomer, about 5% to about 25% of a gamma-delta unsaturated isomer, and about 5% to about 10% of a delta-epsilon unsaturated isomer;

(b) Said Component B is a mixture of water soluble salts of bifunctionally-substituted sulfur-containing saturated aliphatic compounds containing from about 10 to about 24 carbon atoms, the functional units being hydroxy and sulfonate radicals with the sulfonate radical always being on the terminal carbon and the hydroxyl radical being attached to a carbon atom at least two carbon atoms removed from the terminal carbon atom; and

(c) Said Component C is a mixture comprising from 30-95% water-soluble salts of alkene disulfonates containing from about 10 to about 24 carbon atoms, and from about 5% to about 70% water-soluble salts of hydroxy disulfonates containing from about 10 to about 24 carbon atoms, said alkene disulfonates containing a sulfonate group attached to a terminal carbon atom and a second sulfonate group attached to an internal carbon atom not more than about six carbon atoms removed from said terminal carbon atom, the alkene double bond being distributed between the terminal carbon atom and about the seventh carbon atom, said hydroxy disulfonates being saturated aliphatic compounds having a sulfonate radical attached to a terminal carbon, a second sulfonate group attached to an internal carbon atom not more than about six carbon atoms removed from said terminal carbon atom, and a hydroxy group attached to a carbon atom which is not more than about four carbon atoms removed from the site of attachment of said second sulfonate group.

(B) NONIONIC SYNTHETIC DETERGENTS

Nonionic synthetic detergents may be broadly defined as compounds produced by the condensation of alkylene oxide groups (hydrophilic in nature) with an organic hydrophobic compound, which may be aliphatic or alkyl aromatic in nature. The length of the hydrophilic or polyoxyalkylene radical which is condensed with any particular hydrophobic group can be readily adjusted to yield a water-soluble compound having the desired degree of balance between hydrophilic and hydrophobic elements.

For example, a well known class of nonionic synthetic detergents is made available on the market under the trade name of "Pluronic." These compounds are formed by condensing ethylene oxide with a hydrophobic base formed by the condensation of propylene oxide with propylene glycol. The hydrophobic portion of the molecule which, of course, exhibits water insolubility, has a molecular weight of from about 1500 to 1800. The addition of polyoxyethylene radicals to this hydrophobic portion tends to increase the water solubility of the molecule as a whole and the liquid character of the product is retained up to the point where polyoxyethylene content is about 50% of the total weight of the condensation product.

Other suitable nonionic synthetic detergents include:

(1) The polyethylene oxide condensates of alkyl phenols, e.g., the condensation products of alkyl phenols having an alkyl group containing from about 6 to 12 carbon atoms in either a straight chain or branched chain configuration, with ethylene oxide, the said ethylene oxide being present in amounts equal to 5 to 25 moles of ethylene oxide per mole of alkyl phenol. The alkyl substituent in such compounds may be derived from polymerized propylene, diisobutylene, octene, or nonene, for example.

(2) Those derived from the condensation of ethylene oxide with the product resulting from the reaction of propylene oxide and ethylene diamine. For example, compounds containing from about 40% to about 80% poly-

oxyethylene by weight and having a molecular weight of from about 5,000 to about 11,000 resulting from the reaction of ethylene oxide groups with a hydrophobic base constituted of the reaction product of ethylene diamine and excess propylene oxide, said base having a molecular weight of the order of 2,500 and 3,000, are satisfactory.

(3) The condensation product of aliphatic alcohols having from 8 to 22 carbon atoms, in either straight chain or branched chain configuration, with ethylene oxide, e.g., a coconut alcohol-ethylene oxide condensate having from 5 to 30 moles of ethylene oxide per mole of coconut alcohol, the coconut alcohol fraction having from 10 to 14 carbon atoms.

(4) Nonionic detergents include nonyl phenol condensed with either about 10 or about 30 moles of ethylene oxide per mole of phenol and the condensation products of coconut alcohol with an average of either about 5.5 or about 15 moles of ethylene oxide per mole of alcohol and the condensation product of about 15 moles of ethylene oxide with one mole of tridecanol.

Other examples include dodecylphenol condensed with 12 moles of ethylene oxide per mole of phenol; dinonylphenol condensed with 15 moles of ethylene oxide per mole of phenol; dodecyl mercaptan condensed with 10 moles of ethylene oxide per mole of mercaptan; bis-(N-2-hydroxyethyl) lauramide; nonyl phenol condensed with 20 moles of ethylene oxide per mole of nonyl phenol; myristyl alcohol condensed with 10 moles of ethylene oxide per mole of myristyl alcohol; lauramide condensed with 15 moles of ethylene oxide per mole of lauramide; and di-isooctylphenol condensed with 15 moles of ethylene oxide.

(5) A detergent having the formula $R^1R^2R^3N \rightarrow O$ (amine oxide detergent) wherein R^1 is an alkyl group containing from about 10 to about 28 carbon atoms, from 0 to about 2 hydroxy groups and from 0 to about 5 ether linkages, there being at least one moiety of R^1 which is an alkyl group containing from about 10 to about 18 carbon atoms and 0 ether linkages, and each R^2 and R^3 are selected from the group consisting of alkyl radicals and hydroxyalkyl radicals containing from 1 to about 3 carbon atoms;

Specific examples of amine oxide detergents include:

dimethyldodecylamine oxide
dimethyltetradecylamine oxide
ethylmethyltetradecylamine oxide
cetyltrimethylamine oxide
dimethylstearylamine oxide
cetylpropylamine oxide
diethyldodecylamine oxide
diethyltetradecylamine oxide
dipropyldecylamine oxide
bis-(2-hydroxyethyl)dodecylamine oxide
bis-(2-hydroxyethyl)-3-dodecoxy-1-hydroxypropyl
amine oxide
(2-hydroxypropyl)methyltetradecylamine oxide
dimethyloleyamine oxide
dimethyl-(2-hydroxydodecyl)amine oxide

and the corresponding decyl, hexadecyl and octadecyl homologs of the above compounds.

(6) A detergent having the formula $R^1R^2R^3P \rightarrow O$ (phosphine oxide detergent) wherein R' is an alkyl group containing from about 10 to about 28 carbon atoms, from 0 to about 2 hydroxy groups and from 0 to about 5 ether linkages, there being at least one moiety of R' which is an alkyl group containing from about 10 to about 18 carbon atoms and 0 ether linkages, and each of R^2 and R^3 are selected from the group consisting of alkyl radicals and hydroxyalkyl radicals containing from 1 to about 3 carbon atoms.

Specific examples of the phosphine oxide detergents include:

dimethyldodecylphosphine oxide
dimethyltetradecylphosphine oxide
5 ethylmethyltetradecylphosphine oxide
cetyltrimethylphosphine oxide
dimethylstearylphosphine oxide
cetylpropylphosphine oxide
diethyldodecylphosphine oxide
10 diethyltetradecylphosphine oxide
dipropyldecylphosphine oxide
bis-(hydroxymethyl)dodecylphosphine oxide
bis-(2-hydroxyethyl)dodecylphosphine oxide
(2-hydroxypropyl)methyltetradecylphosphine oxide
15 dimethyloleylphosphine oxide, and
dimethyl-(2-hydroxydodecyl)phosphine oxide
and the corresponding decyl, hexadecyl, and octadecyl homologs of the above compounds.

20 (7) A detergent having the formula

(sulfoxide detergent) wherein R^1 is an alkyl radical containing from about 10 to about 28 carbon atoms, from 0 to about 5 ether linkages and from 0 to about 2 hydroxyl substituents, at least one moiety of R^1 being an alkyl radical containing 0 ether linkages and containing from about 10 to about 18 carbon atoms, and wherein R^2 is an alkyl radical containing from 1 to 3 carbon atoms and from one to two hydroxyl groups.

octadecylmethyl sulfoxide
dodecylmethylsulfoxide
tetradecyl methyl sulfoxide
35 3-hydroxytridecyl methyl sulfoxide
3-methoxytridecyl methyl sulfoxide
3-hydroxy-4-dodecoxybutyl methyl sulfoxide
octadecyl 2-hydroxyethyl sulfoxide
dodecylethyl sulfoxide

(C) AMPHOLYTIC SYNTHETIC DETERGENTS

Ampholytic synthetic detergents can be broadly described as aliphatic derivatives of heterocyclic secondary and tertiary amines, in which the aliphatic radical may be straight chain or branched and wherein one of the aliphatic substituents contains from about 8 to 18 carbon atoms and at least one contains an anionic water-solubilizing group, e.g., carboxy, sulfo, sulfato, phosphate, or phosphono. Examples of compounds falling within this definition are sodium

3-(dodecylamino)-propionate

55 sodium 3-(dodecylamino)propane-1-sulfonate

60 sodium 2-(dodecylamino)ethyl sulfate

sodium 2-(dimethylamino)octadecanoate

65 70 disodium 3 - (N-carboxymethyl)dodecylamino)propane-1-sulfonate

9

disodium 2-(oleylamino)ethyl phosphate

disodium 3 - (N-methylhexadecylamino)propyl - 1 - phosphonate

disodium octadecyl-iminodiacetate

sodium 1-carboxymethyl-2-undecylimidazole, and

disodium 2-[N - (2 - hydroxyethyl)octadecylamino] ethyl phosphate

(D) ZWITTERIONIC SYNTHETIC DETERGENTS

Zwitterionic synthetic detergents can be broadly described as derivatives of aliphatic quaternary ammonium and phosphonium or tertiary sulfonium compounds, in which the cationic atom may be part of a heterocyclic ring, and in which the aliphatic radical may be straight chain or branched, and wherein one of the aliphatic substituents contains from about 8 to 18 carbon atoms, and at least one aliphatic substituent contains an anionic water-solubilizing group, e.g., carboxy, sulfo, sulfato, phosphato or phosphono. Examples of compounds falling within this definition are 3-(N,N-dimethyl-N-hexadecylammonio)-2-hydroxypropane-1-sulfonate

3 - (N,N - dimethyl-N-hexadecylammonio) propane-1-sulfonate

2-(N,N-dimethyl-N-dodecylammonio) acetate

3-(N,N-dimethyl N-dodecylammonio) propionate

2-(N,N-dimethyl-N-octadecylammonio)-ethyl sulfate

2-(trimethylammonio)ethyl dodecylphosphonate

10

ethyl 3-(N,N-dimethyl-N-dodecylammonio)propyl-phosphonate

3-(P,P-dimethyl-P-dodecylphosphonio)propane-1-sulfonate

2-(S-methyl-S-tert-hexadecylsulfonio)ethane-1-sulfonate

3-(S-methyl-S-dodecylsulfonio)propionate

sodium 2-(N,N-dimethyl-N-dodecylammonio)ethyl phosphonate

4-(S-methyl-S-tetradecylsulfonio)butyrate

1-(2-hydroxyethyl)-2-undecylimidazolium-1-acetate

50 2-(trimethylammonio)octadecanoate

and 3-(N,N-bis (2-hydroxyethyl)-N-octadecylammonio)-2-hydroxy-propane-1-sulfonate.

65 Some of these detergents are described in the following U.S. patents: 2,129,264; 2,178,353; 2,774,786; 2,813,898; and 2,828,332.

70 The anionic, nonionic, amphotolytic and zwitterionic detergents mentioned above can be used singly or in combination in the practice of the present invention. However, the anionic detergent surfactants are highly preferred.

75 Examples of water-soluble inorganic alkaline detergency builder ingredients are salts such as alkali metal

carbonates, phosphates, polyphosphates and silicates. Specific examples of such salts are sodium and potassium tripolyphosphates, carbonates, pyrophosphates, phosphates and hexametaphosphates.

Examples of organic alkaline sequestrant builder ingredients that are preferred are (1) alkali metal amino polycarboxylates [e.g., sodium and potassium ethylene diaminetetraacetates, N - (2 - hydroxyethyl) - ethylene diaminetriacetates, nitrilotriacetates, and N - (2 - hydroxyethyl)-nitrilo diacetates]; (2) alkali metal salts of phytic acid [e.g., sodium and potassium phytates—see U.S. Pat. 2,739,943]; (3) water-soluble ethane - 1-hydroxy-1,1-diphosphonates [e.g., preferably the trisodium and tripotassium salts—see U.S. Pat. 3,159,581]; (4) water-soluble salts of methylene diphosphonic acid [e.g., trisodium and tripotassium methylene diphosphonate and other salts described in U.S. Pat. 3,213,030]; (5) water-soluble salts of substituted methylene diphosphonic acids [e.g., trisodium and tripotassium ethylidene, isopropylidene, benzylmethylidene and halomethylidene diphosphonates and the other substituted methylene diphosphonates disclosed in the copending application of Clarence H. Roy, Ser. No. 266,055, filed Mar. 18, 1963 and now U.S. Pat. 3,422,021]; (6) water-soluble salts of polycarboxylic acid polymers and copolymers as described in the copending application of Francis L. Diehl, Ser. No. 269,359, filed Apr. 1, 1963 and now U.S. Pat. 3,308,067 [e.g., polymers of itaconic acid, aconitic acid; maleic acid; mesaconic acid; fumaric acid; methylene malonic acid; and citraconic acid and copolymers with themselves and other compatible monomers such as ethylene]; and (7) mixtures thereof.

Mixtures of any and all of the organic and/or inorganic builders can be used and are generally desirable. Especially preferred are the mixtures of builders disclosed in the copending application of Burton H. Gedge, Ser. No. 398,705, filed Sept. 23, 1964 and now U.S. Pat. 3,392,121, e.g., ternary mixtures of sodium tripolyphosphate, sodium nitrilotriacetate and sodium ethane-1-hydroxy-1,1-diphosphonate. These ternary mixtures can fall within the ternary diagram ABCDEF in the drawing of the copending application of Burton H. Gedge, Ser. No. 398,705, filed Sept. 23, 1964, which drawing is incorporated by reference herein. Binary mixtures of these same three builders, e.g., a mixture containing 10% to 85% of sodium tripolyphosphate and 90% to 15% sodium nitrilotriacetate or a mixture containing 30% to 90% of sodium nitrilotriacetate and 70% to 10% of sodium ethane - 1 - hydroxy - 1,1-diphosphonate, are also preferred as well as a mixture of 30% to 80% of sodium tripolyphosphate with 70% to 20% of sodium ethane-1-hydroxy-1,1-diphosphonate.

The detergent compositions of this invention can contain, if desired, up to about 5% of any of the usual adjuvants, diluents and additives, e.g., moisture, perfumes, other organic detergent surfactants, anti-tarnishing agents, bacteriostatic agents, dyes, fluorescers, and the like, without detracting from the advantageous properties of the compositions.

The detergent compositions of this invention often tend to be corrosive toward aluminum; thus, if the detergent solution is to contact this metal repeatedly or for prolonged periods of time, especially at elevated temperatures, a corrosion inhibitor should be desirably included. Soluble silicates are highly effective inhibitors when added to the compositions of this invention, preferably at levels of from about 3.5% to about 10%. Potassium, or preferably sodium silicates having a weight ratio of $\text{SiO}_2/\text{M}_2\text{O}$ of from about 1.0 to about 2.6 and preferably from 1.6 to about 2.6 can be used. M in this ratio refers to sodium or potassium.

In the embodiment of this invention which provides for a built liquid detergent, a hydrotropic agent may at times

be found desirable. Suitable hydrotropes are water-soluble alkali metal salts of toluenesulfonate, benzenesulfonate and xylenesulfonate. The preferred hydrotropes are the potassium or sodium toluenesulfonates. The hydrotrop salt may be added, if desired, at levels of 0% to about 12%. While a hydrotrope will not ordinarily be found necessary, it can be added if so desired for any reason such as to produce a product which retains its homogeneity at a low temperature.

The following built detergent compositions, in which the percentages are by weight, will serve to more fully illustrate the invention:

BUILT LIQUID DETERGENT COMPOSITION

	Percent
15 Sodium dodecylbenzenesulfonate (the dodecyl radical being derived from polypropylene, predominantly tetrapropylene averaging 12 carbon atoms)	6.0
20 Dimethyldodecylamine oxide	6.0
Trisodium ethane-1-hydroxy-1,1-diphosphonate	20.0
Potassium toluenesulfonate	8.0
Sodium silicate (ratio $\text{SiO}_2/\text{Na}_2\text{O}$ of 2.45:1)	3.8
25 Antiredeposition agent consisting essentially of 65% Sodium CMC having a DS of 0.6 and a DP of 1600, and 35% HPC having an MS of 2.0 and a DP of 265	0.1
Water balance.	

BUILT GRANULAR DETERGENT COMPOSITION

	Percent
30 Sodium dodecylbenzenesulfonate (dodecyl group derived from tetrapropylene)	17.5
Sodium tallow alkyl sulfate	3.5
35 Sodium tripolyphosphate	47.0
Sodium silicate (ratio $\text{SiO}_2/\text{Na}_2\text{O}$ of 2:1)	6.0
Sodium sulfate	20.8
40 Cocount fatty acid ethanolamide	2.7
Perfume and optical brightener	1.0
45 Antiredeposition agent consisting essentially of 80% Potassium CMC having a DS of 0.8 and a DP of 1000, and 20% HPC having an MS of 2.0 and a DP of 900	1.2
Moisture balance.	

BUILT GRANULAR DETERGENT COMPOSITION

	Percent
50 Sodium linear dodecylbenzenesulfonate	7.5
Nonionic detergent (a mixture of 1.5% Ucon and 5% Pluronic L-64) ¹	2.0
Hydrogenated marine oil fatty acid	2.2
55 Trisodium ethane-1-hydroxy-1,1-diphosphonate	59.6
Sodium silicate (ratio $\text{SiO}_2/\text{Na}_2\text{O}$ of 2:1)	9.7
Sodium sulfate	13.5
55 Perfume and optical brightener	1.0
Antiredeposition agent consisting essentially of 75% Ammonium CMC having a DS of 0.5 and a DP of 700, and 25% HPC having an MS of 3.0 and a DP of 1100	0.5
60 Water balance.	

BUILT GRANULAR DETERGENT COMPOSITION

	Percent
65 Sodium linear dodecylbenzenesulfonate	20.0
Potassium toluenesulfonate	2.0
Trichlorocarbanilide (as a bacteriostat)	0.5
Sodium tripolyphosphate	30.0
Sodium silicate (ratio $\text{SiO}_2/\text{Na}_2\text{O}$ of 2:1)	6.0
Sodium sulfate	32.3
70 Fatty acid ethanolamide	1.6
Antiredeposition agent consisting essentially of 80% Sodium CMC having a DS of 0.7 and a DP of 1600, and 20% HPC having an MS of 2.5 and a DP of 900	0.8
75 Water	6.8

BUILT LIQUID DETERGENT COMPOSITION

	Percent
3(N,N - diethyl - N - hexadecylammonio) - 2-hydroxypropane-1-sulfonate	12.0
Trisodium ethane-1-hydroxy-1,1-diphosphonate	20.0
Sodium silicate ($\text{SiO}_2:\text{Na}_2\text{O}=1.6:1$)	3.8
Potassium toluenesulfonate	8.5
Fluorescent dye	.12
Perfume	.15
Benzotriazole	.02
Antiredeposition agent consisting essentially of 70% Sodium CMC having a DS of 0.9 and a DP of 1800, and 30% HPC having an MS of 2.4 and a DP of 1060	.6
Water	54.4

¹ Ucon and L-64 are condensation products of ethylene oxide with a hydrophobic base formed by the condensation of propylene oxide with propylene glycol and having molecular weights of approximately 3000 and 8000 respectively.

BUILT GRANULAR DETERGENT COMPOSITION

	Percent
3 - (N,N-dimethyl-N-hexadecylammonio) - propane-1-sulfonate	17.0
Of a 1:1:1 mixture of trisodium ethane-1-hydroxy-1,1-diphosphonate, sodium tripolyphosphate and sodium nitrilotriacetate	45.0
Sodium-silicate ($\text{Na}_2\text{O}:\text{SiO}_2=1:2.5$)	6.0
Sodium sulfate	28.0
Antiredeposition agent consisting essentially of 78% Sodium CMC having a DS of 0.7 and a DP of 1400, and 22% HPC having an MS of 2.5 and a DP of 650	0.4
Water	3.5
Miscellaneous balance.	

Excellent cleaning performance and whiteness maintenance (antiredeposition) results are obtained by laundering with all of the above compositions.

The following antiredeposition experiments were performed in order to illustrate the efficacy of the novel antiredeposition agent of this invention on cotton, synthetics and synthetic-cotton blends. The experiments were conducted as specified below:

SOIL COMPOSITION

0.02 g./l. carbon black (Interchemical Lampblack #10)	
0.40 g./l. simulated natural soil having the composition:	
	Percent by weight
Saturated fatty acids (total)	26.72
Lauric acid (C_{12})	1.75
Myristic acid (C_{14})	5.57
Palmitic acid (C_{16})	11.15
Stearic acid (C_{18})	5.90
$\text{C}_{20}-\text{C}_{22}$ acid	1.90
Other saturated acids	0.45
Unsaturated fatty acids (total)	9.88
Oleic acid (C_{18})	7.59
Linoleic acid (C_{18})	1.38
Other unsaturated acids	0.91
Coconut oil	3.30
Tallow	29.70
Paraffin wax	7.30
Squalene	3.70
Lanolin	19.40

The ingredients of the simulated natural soil were combined by heating and mechanically stirring.

DETERGENT COMPOSITION

2.5 g./l. conventional built granular detergent having the composition:

	Percent by weight
5 Sodium dodecylbenzenesulfonate, dodecyl derived from tetrapropylene (ABS)	20.0
Sodium tripolyphosphate (STP)	50.0
Sodium sulfate (Na_2SO_4)	24.0
Sodium silicate	6.0

10 Antiredeposition agent as specified.

HARDNESS

7 grains per U.S. gallon (120 p.p.m. CaCl_2)

CLOTH LOAD

3½" x 3½" swatches weighing a total of 14.3 g.±0.3 g. and comprising: five cotton muslin swatches, four nylon swatches, and four Dacron® swatches

EQUIPMENT

20	Waring blender (5 cup size)
	Tergotometer having four 1-liter beakers (U.S. Testing Co.)
	Hunterlab color-difference meter
25	Circulating air oven
	Clothes wringer

PROCEDURE

(1) The amounts of ingredients required for four liters of washing solution (four beakers) were calculated.

(2) The ingredients were weighed in the following order and transferred to the Waring Blender.

- (a) STP
- (b) Na_2SO_4
- (c) CaCl_2
- (d) Carbon black
- (e) Soil
- (f) Sodium silicate
- (g) 100 ml. aqueous ABS solution containing the required amount of ABS

(3) The volume in the blender was increased with demineralized water to 1½ cups and the contents were agitated for thirty minutes.

- 45 (4) The concentrated mix was then transferred to a 1 liter graduate using demineralized water to aid in a quantitative transfer. The volume in the graduate was diluted to one liter with demineralized water and the contents of the graduate were transferred to a 3-liter beaker and then diluted to two liters with two 500-ml. portions of demineralized water. The mixture was kept agitated and divided into four equal portions in 1-liter graduates. The mixtures were then diluted to one liter and transferred to the Tergotometer beakers.
- 50 (5) The pH of each solution was adjusted to 10.0.

(6) The beakers were placed in the Tergotometer bath which was preheated at 142° F., and the agitators started.

- (7) The antiredeposition agents to be tested were transferred from a weighing bottle to the wash solution in the Tergotometer beakers, and given time to dissolve.

- (8) After the wash solution had reached the desired temperature (140° F.), agitation was stopped, the fabrics were added as rapidly as possible (one swatch at a time), and agitation was resumed and continued for one hour at 110 cycles/minute.

- (9) The fabrics were removed and passed through a wringer. The fabrics were put in clean (7 grain hardness) water at room temperature and rinsed for two minutes at 110 cycles/min. The temperature rose slightly during the rinse since the beakers were in the heated Tergotometer bath.

(10) The fabrics were removed, squeezed by hand, spread out on a blotter and dried for one hour at 65° C.

- (11) The cloth swatches were ironed with a medium temperature iron (rayon setting) and read on the Hunter-

lab Color Difference meter; the whiteness values were calculated in whiteness units (W) using the equation:

$$W=100-\sqrt{(100-L)^2+2.25(a^2+b^2)}$$

where L is the grayness (or lightness) value, a is the redness value and b is the yellowness value ($-a$ and $-b$ are greenness and blueness respectively).

(12) Based on a statistical study of seventeen prior tests, it was calculated that a significant and real difference in antiredeposition effect existed in the following increments:

Nylon—0.66 whiteness units
Dacron®—0.67 whiteness units
Cotton—1.30 whiteness units

Example I

A series of 22 tests were performed to illustrate the effects of (1) varying the proportions of NaCMC and HPC in the antiredeposition agent and (2) varying the total concentration of antiredeposition agent. The NaCMC was a highly preferred species having a DS of 0.7 and a DP of 1500.² The HPC was also a highly preferred species having an MS of 2.4 and a DP of 1050. The data are tabulated in Table I and plotted graphically in FIGS. I through IV.

In Table I, W' is the average number of whiteness units obtained when no antiredeposition agent was used. For nylon, the value of W' was obtained by calculating the average of tests 1 (75.9), 3 (76.3), 11 (73.3), 15 (73.4), and 19 (73.1) which equals 74.6. For Dacron®, W' was 72.3 and for cotton it was 85.2. The values of Columns I, J, and K were obtained by subtracting the W' (average whiteness obtained for each material without an antiredeposition agent) from W, the actual measured whiteness value obtained with an antiredeposition agent.

5

FIG. II is a plot of the data from tests 4, 8, 12 and 16. More specifically, FIG. II illustrates the antiredeposition value ($W-W'$) of HPC used alone. It can be seen from

FIG. II that HPC exhibits a high level of antiredeposition efficacy with regard to nylon and Dacron® (Columns

I and J of Table I), but exhibits an adverse antiredeposition effect with cotton (Column K of Table I).

FIG. III is a plot of the data from tests 20, 21 and 22. More specifically, FIG. III illustrates the antiredeposition effect of a preferred antiredeposition agent of the present invention comprising 71% NaCMC and 29% HPC. It can be clearly seen from FIG. III that this NaCMC—HPC combination exhibits a high level of antiredeposition efficacy with regard to both cotton and synthetic fabrics.

10 FIG. IV is a plot of the data from all tests 1 through 22, excluding tests 16 and 20. More specifically, FIG.

15 FIG. IV illustrates the antiredeposition value ($W-W'$) of various NaCMC—HPC combinations used in amounts within the range of from 0.20% to 1.2%. It can be seen from FIG. IV that for a high level of antiredeposition efficacy to be achieved with both cotton and synthetic fabrics, the antiredeposition agent must contain about 40–95% NaCMC and about 5–60% HPC. Below about

20 5% HPC, a significant antiredeposition effect on synthetic fabrics is not realized. Above about 60% HPC, a significant antiredeposition effect on cotton is not realized.

25 FIG. IV also illustrates the overall preferred results obtained with a NaCMC—HPC combination containing 60–80% NaCMC and about 20–35% HPC. FIG. III further illustrates the highly preferred results obtained with an NaCMC—HPC combination containing about

30 71% NaCMC and about 29% HPC.

35 In this example, substantially equivalent results are obtained when the NaCMC is replaced by another alkali

TABLE I.—EFFECT OF CONCENTRATION OF HPC, NACMC AND HPC-CMC COMBINATIONS ON ANTIREDEPOSITION

Test:	Antiredeposition Agent										Antiredeposition value, $W-W'$

22	0.29	0.12	0.41	71	29	87.1	87.5	92.7	12.5	15.2	7.5		

Average W' (No antiredeposition agent) Nylon 74.6, Dacron® 72.3, Cotton 85.2.

FIG. I is a plot of the data from tests 5, 9, 13 and 17. More specifically, FIG. I illustrates the antiredeposition value ($W-W'$) of NaCMC used alone. It can be seen from FIG. I that NaCMC exhibits a high level of antiredeposition efficacy with regard to cotton (Column K of Table I), but exhibits essentially no antiredeposition effect with nylon and Dacron® (Columns I and J of Table I).

² The NaCMC was comprised of 61% pure NaCMC; the balance consisted essentially of sodium chloride. Concentrations are expressed in Table I and in the figures on an active NaCMC basis.

65 metal CMC wherein the alkali metal is selected from the group consisting of potassium, lithium and ammonium.

Example II

70 A series of 13 tests were performed to illustrate the effect of varying the MS and DP of HPC. The varying HPC compositions were tested in a preferred antiredeposition agent comprising 71% HPC and 29% NaCMC. The antiredeposition agent was used in a preferred amount of 0.4% by weight based on the amount of

detergent composition. The data are tabulated below in Table II and plotted graphically in FIG. V.

TABLE II.—EFFECT OF HPC, MS AND DP IN A PREFERRED NaCMC-HPC ANTIREDEPOSITION AGENT

HPC composition (MS-DP)	Whiteness units (W)			Antiredeposition Value		
	Nylon	Dacron®	Cotton	Nylon	Dacron®	Cotton
Test:						
23-----	0.7-1, 400	77.2	76.4	88.6	3.8	3.7
24-----	0.7-2, 300	76.6	78.5	89.9	3.2	5.8
25-----	1.3-265	84.1	85.2	89.0	10.7	12.5
26-----	1.5-640	85.3	87.1	89.4	11.9	14.4
27-----	1.2-900	84.4	84.9	85.1	11.0	12.2
28-----	1.1-2, 000	81.3	83.0	85.7	7.9	10.3
29-----	2.0-265	86.1	86.8	91.9	12.7	14.1
30-----	2.1-640	86.7	87.7	92.4	13.3	15.0
31-----	2.1-1, 400	82.8	86.2	84.1	9.4	13.5
32-----	2.1-2, 300	83.9	87.6	85.1	10.5	14.9
33-----	2.8-900	87.4	88.6	92.2	14.0	15.9
34-----	2.6-2, 000	83.8	87.8	87.5	10.4	15.1
35-----	2.4-1, 050	87.2	88.1	92.5	13.8	15.4
						7.2

Average W' (No anti-redeposition agent) nylon 73.4, Dacron® 72.7, Cotton 85.3.

FIG. V is a plot of the data from tests 23 through 35

FIG. V is scaled so that a vertical distance as indicated in the lower left hand corner of FIG. V corresponds to an antiredeposition value ($W-W'$) of 10 whiteness units.

It can be seen from FIG. V that an unexpectedly high level of antiredeposition efficacy is achieved with cotton and synthetic fabrics when the HPC contained in the NaCMC—HPC combination has an MS greater than about 2.0 and a DP within the range of from 100 to about 1200. FIG. V further illustrates the highly preferred results obtained when the HPC contained in the NaCMC—HPC combination has an MS within the range of from about 2.0 to about 3.5 and a DP within the range of from about 600 to about 1100.

Example III

A series of four tests were performed to illustrate the effect of this invention's antiredeposition agent on fabric comprised of a synthetic-cotton blend. The composition of the NaCMC and HPC was the same as in Example I, supra. The synthetic-cotton blend was a fabric containing 65% Dacron® and 35% cotton obtained from Testfabrics Inc., New York, and designated as style 7400A shirting. The data are tabulated in Table III.

TABLE III.—EFFECT OF CONCENTRATION OF HPC, NaCMC AND HPC-CMC COMBINATION ON ANTIREDEPOSITION WITH FABRIC COMPRISED OF SYNTHETIC-COTTON BLEND

Test:	Antiredeposition Agent						
	Percent by weight based on amount of detergent composition			Percent by weight in antiredeposition agent		Whiteness units (W)	Antiredeposition value, $W-W'$
	NaCMC	HPC	Total	NaCMC	HPC		
36-----	0	0	0	0	0	78.2	-----
37-----	0.0	0.12	0.12	0	100	84.4	6.2
38-----	0.29	0.0	0.29	100	0	79.1	0.9
39-----	0.29	0.12	0.41	71	29	85.5	7.3

It can be observed from Table III that a NaCMC—HPC combination of the invention (test 39) is superior in antiredeposition efficacy with a synthetic-cotton fabric as compared to either NaCMC (test 38) or HPC (test 37) individually.

What is claimed is:

1. A composition consisting of a built detergent composition containing 20% sodium dodecylbenzenesulfonate, 50% sodium tripolyphosphate, 24% sodium sulfate and 6% sodium silicate, and from about 0.1% to about

1.2% based on the amount of detergent composition, of an antiredeposition agent consisting essentially of:

(a) about 71% sodium carboxymethylcellulose having a degree of substitution of about 0.7 and a degree of polymerization of about 1500; and

(b) about 29% hydroxypropylcellulose having an MS of about 2.8 and a degree of polymerization of about 900.

2. A composition consisting of a built detergent composition containing 20% sodium dodecylbenzenesulfonate, 50% sodium tripolyphosphate, 24% sodium sulfate and 6% sodium silicate, and from about 0.1% to about 1.2% based on the amount of detergent composition, of an antiredeposition agent consisting essentially of:

(a) about 71% sodium carboxymethylcellulose having a degree of substitution of about 0.7 and a degree of polymerization of about 1500; and

(b) about 29% hydroxypropylcellulose having an MS of about 2.4 and a degree of polymerization of about 1050.
